YARN SUBSTITUTE FOR KNITTING OR CROCHETING ACTIVITIES AND THE METHOD OF MAKING THE SAME

Eileen B. Knowles, Forbestown, Calif.

Application November 9, 1945, Serial No. 627,556

6 Claims. (Cl. 66—202)

1

This invention relates to yarn substitutes for knitting or crocheting activities, and the method of making the same, and has particular relation to a string or strand laden with soft and fine fur fibers of animal source for use as a substitute for yarn in the fashioning of articles by knitting or crocheting, together with the method of producing such strand or string.

The principal object of the invention is the production of a strand or string of this type which, when used in fashioning the article as by knitting or crocheting, is used similar to and as a substitute for the yarn generally employed, and which article, when thus fashioned, will present an exposed face of fluffy appearance with the face simulating a blanket of fur of an especially soft and fluffy type (in practice both of the opposite faces of the article fabric present such appearance), with the article presenting characteristics of warmth, washability, and long life, the invention comprising a strand or string of this type, the method of producing the same, and a fabric made therefrom.

To these and other ends, the nature of which will be readily understood as the invention is hereinafter set forth, said invention consists in a strand or string of this type and the method of producing the same, all as hereinafter more fully described, illustrated in the accompanying drawings, and more particularly defined in the appended claims.

In the accompanying drawings, in which similar reference characters indicate similar parts in each of the views,

Figure 1 is a perspective view showing a length of the completed strand or string.

Figure 2 is a perspective view of one form of crocheting stitch usable in producing the strand or string, the view showing a short length of the base thread of the strand or string crocheted with the several formations in very loose form—the view being purposed to illustrate one form of crochet stitch which may be employed, the view simply illustrating one form of stitch development.

Figure 3 is a perspective view of the stitch of Figure 2 in the tight form which is used in producing the strand or string—the view omits the fur content which is incorporated during the production of the stitch.

Figure 4 is a perspective view, partly in section, of a fabric section produced by knitting or crocheting the strand or string of Figure 1, and illustrating some of the characteristics present in a fashioned article.

2

The strand or string which constitutes the present invention—indicated at 10—is formed from a thread—coarse or fine—11, and increments of soft and fine fur fibers indicated at 12. The thread 10 may be of silk, cotton, rayon, or other fibrous material which is more or less inelastic; nylon thread may also be used where the article to be produced is never subjected to a strain or stress sufficient to develop the inherent "stretch" characteristic present in this material; wool thread is unsuitable due to its shrinking possibilities which would prevent washing of the article.

The fur fibers content is the soft and fine fibers secured from the pelts of certain animals—rabbit does are a preferred source—the fibers being removed from the skin of the pelt. Coarse and stiff fiber is unsuitable due to its inability to produce the desired fluffy blanket-like appearance, the latter presenting the softness of down but is actually of animal fiber; to illustrate somewhat of the animal selection, the hair of the Angora species is more or less objectionable due to its having some of the characteristics of wool. The length of the fur fibers is not great—too short to be spun—but is sufficient to provide a material portion extending to opposite sides of its thread carrier, when positioned cross-wise of the direction of length of the chain thread formation.

The thread is formed into the strand or string base by crocheting, the latter serving to provide certain loop effects through which small increments of fur fibers are passed after which the loops are tightened about the mid-zone of the fiber length, to retain the fibers in place within the string or strand or the article which may be formed from the latter; hence, no adhesive of any kind is used in the production of the strand or string, the firm binding of the mid-zone of the fiber increments, coupled with the freedom of the end zones of the fibers to move laterally, serving to maintain the fibers in position.

In crocheting the thread, the selected stitch used in forming the loops should be such as to provide somewhat of a locking action—an illustrative stitch is shown in a loose formation in Figure 2—the stitch of which is of a simple chain type modified to provide the locking feature; the loose form of Figure 2 is not used in practice, since this stitch cannot be tightened or lengthened after the stitch has left the crocheting needle, but when tightened by the needle activities produces the appearance of Figure 3 if the fiber increments are not introduced.

The locking feature of the stitch is more or

less essential to prevent change in the dimensions of the loop—if the dimensions of the latter are increased in service, the fur fibers can readily escape from the loop, and if the dimensions are made smaller (as by shrinkage of the thread material) the increased pressure could break the fine fiber; in either case, the appearance characteristics of the article would be affected through loss of fur fibers. This can illustrate reasons for the undesirability of the use of wool or of fur fibers having characteristics of wool—shrinking of the cross-sectional dimensions of the fur fibers could produce a looseness of the bound fiber increments and thus set up copious shedding possibilities.

As is apparent the length of the individual fibers is not uniform, when taken from the pelts, and this condition is not changed when located within the strand; each increment is made up of a promiscuous group of the varied length fibers, so that the projected ends of the fibers set up a non-uniform appearance of the ends of the fiber increments, as indicated in Figure 1; while the strand or string presents this effect, this condition becomes unnoticeable when the string or strand is knitted or crocheted into the article, so far as the exposed faces of the article are concerned, since the soft and fine fibers fold over promiscuously and produce the blanket-like surfaces of the article. Since the increments are formed of small quantities of the individual fibers, the thickness of the blanket-like surface of the article is not great, but the many fibers used in the aggregate, and which are uniformly distributed by the crocheting of the strand or string, makes it apparent that the article surface will present the appearance of a solid fur surface of very soft characteristic—the down effect—and the unevenness of the fringe of fibers at the edges of the article will not be detrimental since they will give visible evidence of the nature of the fur surface, the latter being very fluffy in appearance.

The loop must be sufficiently large as to readily receive the fiber increment; but to retain the increment in its desired position the loop must be tight about the increment; hence the increment should be inserted during the fashioning of the loop which is to receive it. If a loose chain were provided, the increments then inserted, and the loops then tightened by drawing on the chain, the product would be unstable since the chain loops could be drawn out into the loose form and release the fiber increments. Hence the stitch used in developing the strand or string should include a locking characteristic which prevents material change in the dimensions of the loop after the loop has been completed and leaves the needle, since the latter must provide the tightening action.

Hence, the fiber increments are fed, in suitable manner, into the embryo loop during its formation. This can be a hand or a machine operation—as can be the crocheting of the strand or string; in hand crocheting, the fibers may be placed convenient and so arranged as to permit rapid pick-up of the desired increment, fed into the embryo loop and the loop tightened—it is possible that the needle hook can be employed to pick-up and feed the increment into the embryo loop and the latter then be completed about the positioned increment. Because of the varied possibilities as to the form of the stitch and the ways of feeding the increments no particular showing in this respect is being made in the draw-

ings, it being understood that the particular form of the stitch will determine the crocheting regimen, and the particular forming of the increments and feeding thereof into the embryo loop may be by the fingers, the use of tweezers or even a machine, so that the timing of the feeding and the particular feeding technique may depend on the particular form of stitch being used. In each instance, however, the increment is fed into the embryo loop formation and the latter is then tightened about the positioned increment, the increment being held therein by the locking characteristic of the stitch which prevents the loop from being loosened.

Since the chain stitches usable for developing the string or strand generally provide for more than a single loop within the stitch, it is possible to provide variations in the form of the strand or string by limiting the inserted increment to but a single loop of the stitch or by utilizing all of the loop; the latter will provide a deeper blanket effect than the former due to the increase in the number of fibers present; but the number of loops of the stitch used must be sufficient to provide a definite blanketing appearance to the surface of the completed article.

The strand or string thus formed is then used similar to yarn in the fashioning of the article, as by knitting or crocheting, the strand or string thus serving as a substitute for yarn; in other words, the strand or string is treated as though it were a single thread or cord and the knitting or crocheting of the article is carried out on this basis, so that, the completed article would have some of the characteristics such as would be produced by the knitting or crocheting of cord or yarn, but differing as to other characteristics.

For instance, the surfaces of the article have a soft, fluffy, blanketed form and appearance which practically tends to conceal the textile crocheted thread base, and giving the appearance of a soft fur, as well as producing a warmth characteristic in service—this is manifested especially through the fact that the opposite surfaces each have this characteristic, so that warmth is present although the individual blanket is comparatively thin; in this respect, the production of the materials and articles is such that the fabric produced thereby is of a porous type, thus permitting "breathing" through the fabric without destroying the warmth characteristic.

The article is washable and readily dried, without shrinkage or stretching to any material extent—while the strand or string is itself practically inelastic, the article has the ability to adapt itself to the form of the wearer due to the knitting or crocheting activities used in producing the article, doing this without affecting the normal inelasticity of the strand or string used in the fashioning of the article. Flexibility of the article is thus apparent.

Since the practically inflexible strand or string retains its holding characteristics on the fibers within the loops—thus tending to anchor the increments—and the washing of the article tends to maintain the vitality of the fiber content through the addition of moisture thereto, the article is of long-wearing characteristic; since the fluffy surface is due to the soft and fine fiber content, there is no need of combing the "blanket" to preserve the fluffy, down-like effect, so that damage of the article and material shedding of its fur content from this source is absent and the life of the article is thus preserved. And

since the strand or string is itself inelastic and non-shrinking, it is apparent that the life of the article will not be affected by shrinkage although the article may be subjected to frequent washings.

While I have herein shown and described a strand or string of a preferred type, as well as varied ways for producing the same together with a fabric produced therefrom, it is evident that changes or modifications thereof may be found desirable or essential in meeting the various exigencies of use and the desires of individual users, and I therefore reserve the right to make any and all such changes therein as may be found desirable or essential, insofar as the same may fall within the scope of the accompanying claims, when broadly construed.

What is claimed as new is:

1. A yarn substitute in the form of a strand or string comprising a thread base crocheted to provide a succession of loops, and increments of soft and fine fur fibers extending through and anchored by tightened loops of the crocheted chain.

2. A yarn substitute in the form of a strand or string comprising a thread base crocheted to provide a succession of loops, and increments of soft and fine fur fibers extending through and anchored by tightened loops of the crocheted chain with the anchoring provided within the mid zone of the length of the increment to thereby provide lengths of individual fibers projecting freely from opposite sides of the crocheted base.

3. A yarn substitute in the form of a strand or string comprising a thread base crocheted to provide a succession of loops, and increments of soft and fine fur fibers extending through and anchored by tightened loops of the crocheted chain with the anchoring provided within the mid zone of the length of the increment to thereby provide lengths of individual fibers projecting freely from opposite sides of the crocheted base the increment fiber content presenting fibers differing as to length with each increment including a promiscuous number of the varied length fibers.

4. In the production of a knitted or crocheted fabric, wherein a yarn substitute is adapted for fashioning such fabrics by knitting or crocheting operations in similitude to the use of yarn thread for such purpose, and wherein the yarn substi-

tute is in the form of a fur-laden strand or string, the method of producing such strand or string which consists in crocheting a textile thread into a strand or string formation in which the formation includes one or more loops within each crocheted stitch, feeding a small increment of soft and fine fur fibers of animal source into a loop during the formation of the stitch to present the increment ends as projecting beyond and on opposite sides of the loop, and tightening the loop about the positioned increment to thereby anchor the increment with such projected increment ends exposed and with the ends of the fibers individual and free.

5. A method as in claim 4 characterized in that the crocheting stitch is formed with embryo increment-receiving loops in relative loose formation to permit ready insertion of the increment and thereafter tightened in completing the stitch to tighten the loop into a locked anchoring relation about a mid-zone of the positioned increment.

6. A fabric having its opposite faces presenting a soft and fluffy appearance and "feel," said fabric being formed by knitting a fur-laden strand or string, such strand or string comprising a thread base crocheted to provide a succession of loops in chain form and having increments of soft and fine fur fibers of animal origin extending through and anchored by tightened loops of the crocheted chain and with the anchoring provided within the mid-zone of the length of the increment to thereby provide lengths of individual fibers projecting freely from opposite sides of the crocheted base.
